ROUND WORK HOLDING FIXTURE

William T. Brown, Hamden, Conn., assignor to
William Davis, New Haven, Conn.

Application September 29, 1943, Serial No. 504,321

5 Claims. (Cl. 77—63)

This invention appertains to new and useful improvements in work holders, and more particularly to a holder for holding round work during the operation of reaming, tapping, countersinking, et cetera.

An important object of the present invention is to provide a device for holding work of the character stated which will firmly hold the work during the machining operations, after which the work can be instantly released and permitted to fall to a collecting receptacle or other appointed place.

Another important object of the invention is to provide a work holding device of the character stated which is positive acting and substantially fool-proof in all respects.

Other objects and advantages of the invention will become apparent to the reader of the following description.

In the drawings:

Figure 1 represents a top plan view of the holder.

Figure 2 is a side elevational view.

Figure 3 is a transverse sectional view taken on line 3—3 of Figure 1.

Figure 4 is a top plan view of the supporting plate.

Figure 5 is a perspective view of the actuating lever.

Figure 6 is a perspective view of the jaws.

Figure 7 is a sectional view taken substantially on line 7—7 of Figure 1.

Figure 8 is a perspective view of the work rest member.

Referring to the drawings, wherein like numerals designate like parts, it can be seen that numeral 5 denotes a supporting plate having depending side flanges 6 and apertured outstanding supporting flanges 7 through which suitable securing elements may be disposed for securing the structure to a conventional drill press table.

On the plate 5 is a transverse channel 8 in which is disposed a pair of jaws 9, 10, each having a slot 11 therein and each having a V-notched end portion 12, these end portions 12 being in opposed relation.

A depression 13 is provided in the plate 5, this cutting into the bottom of the channel 8, this depression having an arcuate wall 14 and a straight wall 15, and in this operates a work rest 16 (see Fig. 8), one end of which is rounded off, as at 17, to ride the arcuate wall 14. Through the plate 5 from the bottom and opening through the depression 13 is a round opening 18 through which finished work can drop, and it is the func-

tion of the work rest 16 to support the work and prevent the same from falling through the opening until the work thereon has been completed.

Screws 19 are disposed through the slots 11 in the jaws 9, 10, it being preferable that the jaw 9 be held stationary as much as possible while the jaw 10 is left loose to be slid.

A lug 20 rises from one side of the plate 5 and has a threaded opening therethrough for receiving a feed screw 21 which is adapted to bear against the outer end of the jaw 9.

A pivot screw 22 is disposed through the opening 23 of the rest 16 and into an opening 24 in the plate 5. The work rest 16 has an anchor 25, and an anchor 26 rises from the plate 5, and between these anchors is a tension spring 27, normally serving to hold the free end of the rest 16 over the work dispensing opening 18 (see Fig. 1).

An elongated actuating lever 28 has a lug 29 thereon through which a screw 30 is disposed and adapted to engage the jaw 10.

The plate 5 is provided with a second upstanding lug 31 through which a screw 32 is disposed and is located within the path of the foot 33 of a pivotal dog 34. Anchoring means 35, 36 on the dog 34 and plate 5, respectively, serve as attaching points for the ends of a tension spring 37, to hold the hook head 38 of the dog 34 engaged with a shoulder 39 on the adjacent end of the work rest 16.

It can now be seen that by pulling the lever 28 to the dotted line position shown in Figure 1, work can be inserted between the jaws 9, 10 after which, by holding the work and releasing the lever 28, the jaw 10 will be forced against the work in order that the work be clamped between the jaws, and the rest 16 will be in a position shown in Figure 1, with the dog 34 engaging the shoulder 39 of the rest 16.

As soon as the cutting operation has been performed on the work, the lever 28 can be moved to the dotted line position shown in Figure 1, which will result in release of the jaw 10 and movement of the work rest 16 to the left in Figure 1, thus releasing the work so that it will fall through the work dispensing opening 18 in the plate 5.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A work holding device comprising a base

having a work dispensing opening therein, a work rest swingable over the work dispensing opening, jaws on the base for holding work over the work dispensing opening, an operating member on the base for releasing one of the jaws, and actuating the work rest simultaneously.

2. A work holding device comprising a base having a work dispensing opening therein, a work rest swingable over the work dispensing opening, jaws on the base for holding work over the work dispensing opening, an operating member on the base for releasing one of the jaws, and actuating the work rest simultaneously, said actuating member being provided with a rockable pawl engageable with the work rest.

3. A work-holding device comprising a horizontal supporting plate having means to facilitate fastening of the same to a support and provided with a raised portion having a vertical opening therethrough and formed in its upper surface with a channel intersecting said opening, opposed jaws slidably secured in said channel, means to adjust one jaw toward or away from the other jaw, a horizontally swingable work rest pivoted on the supporting plate and movable on a plane below the jaws to cover or uncover said opening, yieldable means acting to swing the work rest in a direction to cover said opening, a horizontally swingable lever pivoted on the supporting plate and having a member for engaging and moving said other jaw toward said one jaw, a hooked dog pivoted on said lever and engageable with the work rest for moving the latter to uncover said opening when the lever is swung to release said other jaw.

4. A work-holding device comprising a horizontal supporting plate having means to facilitate fastening of the same to a support and provided with a raised portion having a vertical opening therethrough and formed in its upper surface with a channel intersecting said open-

ing, opposed jaws slidably secured in said channel, means to adjust one jaw toward or away from the other jaw, a horizontally swingable work rest pivoted on the supporting plate and movable on a plane below the jaws to cover or uncover said opening, yieldable means acting to swing the work rest in a direction to cover said opening, a horizontally swingable lever pivoted on the supporting plate and having a member for engaging and moving said other jaw toward said one jaw, a hooked dog pivoted on said lever and engageable with the work rest for moving the latter to uncover said opening when the lever is swung to release said other jaw, and an abutment in the path of said dog for releasing the latter from the work rest after the latter has uncovered said opening and said other jaw has been released.

5. A work-holding device comprising a horizontal supporting plate having means to facilitate fastening of the same to a support and provided with a raised portion having a vertical opening therethrough and formed in its upper surface with a channel intersecting said opening, opposed jaws slidably secured in said channel, means to adjust one jaw toward or away from the other jaw, a horizontally swingable work rest pivoted on the supporting plate and movable on a plane below the jaws to cover or uncover said opening, yieldable means acting to swing the work rest in a direction to cover said opening, a horizontally swingable lever pivoted on the supporting plate and having a member for engaging and moving said other jaw toward said one jaw, a hooked dog pivoted on said lever and engageable with the work rest for moving the latter to uncover said opening when the lever is swung to release said other jaw, said member for engaging and moving said other jaw embodying a screw adjustable transversely of the lever.
